UNITED STATES PATENT OFFICE.

RALPH M. CALDER, OF PHILADELPHIA, PENNSYLVANIA.

DESIGN FOR A DOOR KNOCKER.

Application filed March 3, 1926. Serial No. 16,761. Term of patent 14 years.

To all whom it may concern:

Be it known that I, RALPH M. CALDER, a citizen of the United States, residing in Philadelphia, Pennsylvania, have invented a certain new, original, and ornamental Design for a Door Knocker, reference being had to the accompanying drawing, in which—

Figure 1, is a face view of a door knocker illustrating my new design;

Figure 2, is a section on the line B—B, Fig. 1, illustrating my new design.

I claim:—

The ornamental design for a door knocker, substantially as shown.

RALPH M. CALDER.
